SANDPAPER BACKING DISK

Harvey H. Legg, 507 Elizabeth Ave., Hattiesburg, Miss.

Filed Feb. 7, 1961, Ser. No. 87,585

3 Claims. (Cl. 51—177)

This invention relates to a novel and useful sandpaper backing disk and more particularly to a sandpaper backing disk specifically adapted for use with rotary type sanders utilized to sand flooring surfaces.

Most flooring surfaces are provided with peripheral shoe moldings and in most instances rotary sanders utilized to sand these flooring surfaces are provided with housings generally circular in plan which enclose the rotary disk to which the sandpaper is secured. The housing of the sander is suitably supported by means of wheels for movement across the flooring surface and the height of the disk of the sanding machine may be adjusted relative to the flooring surface by means of suitable adjusting mechanisms carried by the support wheels of the sander housing. Most rotary sanders are provided with sanding disks slightly smaller than the diameter of the generally circular configuration of the sander housing. The sandpaper secured to the sanding disk is slightly larger than the disk and is adapted to extend radially outwardly beyond the peripheral edge of the disk and beneath the lower edges of the generally circular housing of the sander in order that the flooring may be sanded immediately adjacent the shoe molding disposed about its periphery. The sanding disks are normally constructed of a resilient material such as rubber and are thus relatively thick. The outer marginal portions of the sandpaper extending beyond the peripheral edges of the resilient sanding disk rely mostly upon centrifugal force in order to apply pressure to the area of the flooring immediately adjacent the shoe molding. Inasmuch as this outer marginal portion of the sandpaper carried by the sanding disk is not provided with suitable backing, after a short period of use this marginal portion becomes frayed and is not efficient in sanding the area immediately adjacent the shoe molding. Accordingly, if the flooring is to be sanded correctly, the sandpaper must be changed quite frequently and before the center portion of the sandpaper has been fully used or the areas immediately adjacent the shoe molding are properly not sanded. Thus, in order to complete a sanding operation and to sand the area of the floor immediately adjacent the shoe molding a considerable amount of sandpaper is wasted.

There have in the past been attempts at providing a backing disk for sandpaper provided with a beveled outer periphery edge portion so that the extreme outer marginal portions of the backing disk may pass beneath the lower ends of the generally circular side walls of the housing of the sander. This however results in the rubber backing disk scored in a relatively short time by the undersurfaces of the side walls of the housing as the sander is tilted to one side or the other which causes the backing disk to bend and contact the lower ends of the sander housing side walls.

It is the main object of this invention to provide a backing disk for a rotary floor sander constructed in a manner whereby the disk may be constructed of a diameter sufficient to position the outer peripheral edges in alignment with the outer peripheral surfaces of the generally cylindrical or side walls of the sander housing immediately adjacent the lower ends thereof in order that the entire area of the disk of sandpaper carried by the backing disk will have sufficient backing support.

A further object of this invention, in accordance with the immediately preceding object, is to provide a backing disk constructed of a metallic substance but in a manner

2

whereby individual outer portions of the backing disk may flex without resulting in flexing of the remainder of the backing disk.

Still another object of this invention is to provide a backing disk which will aid in the circulation of cooling air about the motor of the sander.

Another object of this invention, in accordance with the immediately preceding object is to provide a sanding disk which will provide a cushion of the air between the outer peripheral portions of the backing disk and the sandpaper disk secured thereto whereby a more efficient and even pressure may be effected of the sandpaper on the flooring being sanded thereby enabling the life expectancy of the sandpaper disk to be greatly extended.

15 A final object to be specifically enumerated herein is to provide a backing disk which will conform to conventional forms of manufacture, be of simple construction and easy to use so as to provide a device that will be economically feasible, long lasting and relatively trouble free in operation.

20 These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a bottom plan view of the backing disk of the instant invention;

FIGURE 2 is a side elevational view of the backing disk;

FIGURE 3 is a side elevational view of the backing disk shown mounted on a rotary type of sander and with a disk of sandpaper secured thereto;

35 FIGURE 4 is an enlarged fragmentary vertical sectional view taken substantially upon a plane passing through the longitudinal center line of the sander illustrated in FIGURE 3.

40 Referring now more specifically to the drawings the numeral 10 generally designates a conventional form of electric rotary sander. The sander 10 includes a housing generally referred to by the reference numeral 12 which may be formed integrally with the end wall 14 of the sander 10. The sander 10 includes an output shaft 16 which is suitably journaled by means of bearings (not shown) housed within the sander 10. The housing 12 includes an upstanding bore 18 through which the lower end of the output shaft 16 is loosely received. The housing 12 includes upstanding generally circular side walls 20 having lower edges 22.

45 50 The terminal end portion of the output shaft 16 is diametrically reduced and externally threaded as at 24.

55 The backing disk of the instant invention is generally referred to by the reference numeral 26 and includes a circular hub generally referred to by reference numeral 28. The hub 28 has an axial threaded bore 30 formed therethrough and the lower terminal end portion of the output shaft 16 is threadedly engaged in the bore 30.

60 65 70 The hub 28 is generally circular in plan and has an outer face 32 in which there is formed an outer annular recess 34 which defines the outer marginal portions of the hub 28. A metallic backing disk generally referred to by the reference numeral 36 is provided and is generally circular in plan. The disk 30 has a plurality of circumferentially disposed openings 38 formed therein spaced distances inwardly of the outer marginal edge portion of the disk. A plurality of slots 40 indicate each of the openings 38 with the outer periphery of the disk 36 and the slots 40 are curved and have their outer ends disposed in trailing positions relative to their inner ends in the direction of rotation of the backing disk 26. The thin resilient disk 36 has a centrally disposed opening 42

formed therein which receives the center portion 44 of the hub 28 defined by the recess 34. A backing plate 46 and a stiffening plate 48 are each also provided with centrally disposed openings referred to by the reference numerals 50 and 52 which are aligned with the opening 42 and also receive the central portion 44 of the hub 28. Any convenient form of fasteners 54 are passed through the stacked plates 40 and 48 and through the thin resilient disk 36 in order to secure the plates and disk to the hub 28.

The terminal end portion of the output shaft 16 is provided with a threaded blind bore 56 in which a threaded fastener 58 is threadedly engaged in order to secure a disk of sandpaper generally referred to by the reference numeral 60 to the backing disk 26. The disk of sandpaper 60 includes a backing disk 62 with a covering of granular material 64 secured to one face thereof.

It will be noted that the openings 38 are of a greater diameter than the width of the slots 40 and that the backing plate 46 terminates a spaced distance from the outer peripheral edge of the resilient disk 36. In addition, it will be noted that the stiffening plate 48 terminates a spaced distance from the outer peripheral edges of the backing plate 46.

In operation, the sander 10 is operated across the flooring 66. Rotation of the output shaft 16 rotates the backing disk 26 and the outer marginal portions of the resilient disk 36 are thin enough to pass between the lower surfaces 22 of the side walls 20 and the flooring 66 to abut against the shoe molding 68.

The sandpaper disk 62 is of the same size as the resilient disk 36 and therefore also extends outwardly to the outer surfaces of the side walls 20 and abuts against the shoe molding 68.

Upon rotation of the disk 26 in a counterclockwise direction in FIGURE 1 of the drawings the air within the slots 46 is forced outwardly through the slots by centrifugal force thus creating a reduced pressure area in the openings 38. This reduced pressure area creates a reduced pressure in the downwardly opening recess 70 formed by the housing 12 and draws air downwardly from the motor of the sander 10 through the space between the output shaft 16 and the walls of the opening 18. In this manner, circulation of cooling air is drawn through the motor of the sander 10 and passes outwardly between the confronting surfaces of the sanding disk 60 and the resilient disk 36 whereby the sanding disk 60 is cushioned by a layer of air. The air cushion effected by the rotation of the disk 26 greatly increases the life of the sandpaper disk 60 and inasmuch as the outer marginal portion of the resilient disk 36 is divided into resilient fingers 72 by means of the slots 40, each of these resilient fingers may flex independently of the other whereby a more even distribution of pressure is effected on the outer peripheral portions of the sandpaper disk 60. Inasmuch as the sandpaper disk 60 and the resilient disk 36 extend outwardly to the outer surfaces of the side walls 20 of the housing 12, the flooring 66 may be sanded immediately adjacent the shoe molding 68.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and

equivalents may be resorted to, falling within the scope of the invention as claimed.

What is claimed as new is as follows:

1. In combination with a rotary sander of the type having a vertical output shaft whose lower end is enclosed by a generally circular housing having upstanding peripheral side walls defining a downwardly opening recess, a sandpaper backing disk, said backing disk having one side adapted to have a thin disk of sandpaper secured thereto, the other side of said backing disk including means securing said disk to said output shaft for rotation therewith, said one side comprising the outer surface of a thin resilient disk, said disk having circumferentially disposed openings formed therein, a plurality of generally radial slots formed therein communicating at least some of said openings with the outer peripheral edge of said resilient disk, and a thin outer marginal edge portion extending closely beneath the lower edges of said housing, a circular backing plate, the inner face of said resilient disk being secured over the outer face of said backing plate, said backing plate being of a diameter substantially smaller than said resilient disk and having its outer peripheral edge portion disposed inwardly of said walls, said openings being of a diameter greater than the width of said slots, said slots being curved and their outer ends being adapted to trail the inner ends thereof in the direction of rotation of said backing disk, a circular stiffening plate, the inner face of said backing plate being secured over the outer face of said circular stiffening plate, said stiffening plate being of substantially smaller diameter than said backing plate, said openings being disposed inwardly of the outer peripheral portions of said stiffening plate and said stiffening plate and said backing plate having aligned circumferentially spaced openings formed therethrough in registry with said openings formed in said resilient disk.

2. The combination of claim 1, wherein said securing means includes a circular hub having its inner face removably secured to said output shaft, the outer face of said hub having an annular recess formed therein and defining its outer marginal portion, said resilient disk and backing and stiffening plates having centrally aligned openings formed therein, said recess being of a depth equal to the combined thickness of said resilient disk and said plates, the central portion of the outer face of said hub defined by said recess being received in said aligned openings, and means securing said resilient disk and said plates to said hub.

3. The combination of claim 1 wherein said resilient disk is of a diameter such that its outer peripheral edge coincides with the outer peripheral surfaces of at least a portion of said sidewalls.
